APPARATUS FOR ASCERTAINING WEIGHT
OF MATERIALS

Robert McLaughlin, Philadelphia, Pa.

Application August 2, 1932. Serial No. 627,281

11 Claims. (Cl. 265—52)

This invention relates to an apparatus for ascertaining the approximate weight of materials.

The principal object of the invention is to provide apparatus for use in connection with the load of a traveling crane whereby its approximate weight may be quickly, easily and accurately determined. While it is not claimed that apparatus constructed in accordance with this invention will function with micrometer accuracy, the margin of error is, however, so small as to be negligible for all practical purposes.

Another object of the invention is to provide apparatus of the character described wherein the tension of but a certain predetermined portion of the entire load will be imparted to the weight recording means so that the latter need not be of such massive character as though the full tension was imparted thereto.

A further object of the invention is to provide apparatus of the character described which will be possessed of but a minimum number of parts and consequent economy of manufacture.

With these and other objects in view, as will hereinafter be made manifest, the invention resides, in general, in the manner of operation, structural characteristics and combinations of elements illustrated in the accompanying two sheets of drawings, described in the following specification and specifically pointed out in the appended claims.

In the drawings, wherein like characters of reference indicate like parts in the several views,

Figure 1 is a side elevation, somewhat diagrammatic in nature, of a traveling crane and attendant weight indicating apparatus constructed in accordance with and embodying the principles of this invention;

Figure 2 is a side elevation, on a larger scale, of the weight indicating apparatus shown in Figure 1;

Figure 3 is a vertical section on the line III—III of Figure 2;

Figure 4 is a view similar to Figure 2, but illustrating a modification of the invention; and,

Figure 5 is an exaggerated diagrammatic view illustrating the mathematical functions employed in connection with the invention.

Referring, in the first instance, to Figure 1 of the drawings, there is shown a crane house whereon in side pillars 10 support track girders 11 of a crane runway. Mounted upon the girders 11 are rails 12 for the reception and guidance of wheels 13 of a crane bridge 14, the latter, in turn, being provided with rails 15 for the supporting wheels 16 of a trolley 17.

Suspended from the bridge 14 at a point adjacent one end of the same is the customary operator's cage 18, and mounted upon and carried by the trolley 17, in the usual manner, is a winding drum 19 for a suspension cable 20. The ways in which the bridge, the trolley and the drum are controlled and operated from the operator's cage form no part of this invention and no effort is made toward illustration of the same.

Secured to the lower end of the suspension cable 20 is a suspension block 21 and pivotally mounted to this block, at 22, is a hook 23 for engagement with the crane load. While this load may be of any nature, such as a pot or ladle for the reception and transportation of molten metal, a casting, a piece of machinery, or any other article of a kind adapted to be handled by a traveling crane, it is merely conventionally indicated, at 24, in the drawings, for the purpose of illustration.

Rigidly secured to one of the side pillars 10 is a frame 25, in which is slidably mounted a hollow block 26 and slidably mounted in the latter is a cross-head 27. Revolvably secured to the outer face of the block 26 is the head 28 of a screw stem 29, which passes through and is threadedly engaged within a bearing 30 formed on the frame 25 and which terminates, at its outer end, in a crank handle 31.

Inwardly projecting from the cross-head 27 is a rod 32, to the inner end of which is pivotally mounted, as at 33, one end of a link 34, the other end of which is provided with a hook 35 adapted to be engaged with the pivot pin 22 of the suspension block 21. Interposed between the inner face of the cross-head 27 and the corresponding inner face of the hollow block 26, and surrounding the rod 32, is a coiled spring 36.

Fixedly mounted upon the face of the frame 25 is an indicator 37 adapted to cooperate with a similar indicator 38, which is fixedly mounted upon the face of the block 26, and fixedly mounted upon the cross-head 27 is an indicator 39 adapted to cooperate with a poundage scale 40 upon the face of the block 26.

Projecting laterally from the inner and outer members of the hollow block 26 are sight aligning pins 41 and projecting laterally from the suspension block 21, at a point above the pivot pin 22, is a similar sight aligning pin 42.

The operation of the apparatus is as follows:

It is desired to ascertain the approximate weight of the load 24. The bridge and trolley are manipulated to bring the load to a point in

line with the weight indicating means upon the pillar 10. The suspension cable drum is then operated to so raise or lower the load that the sight pin 42 is brought into horizontal alignment with the two sight pins 41, this condition being ocularly determined by the operator sighting along the line of the two pins 41. With the parts in this position, the length of the suspension cable 20 is definitely known. The hook 35 of the link 34 is then engaged with the pivot pin 22 of the suspension block 21 and the crank arm 31 is rotated, feeding the screw stem 29 through the bearing 30 and retracting the hollow block 26 in the frame 25 until the indicator 37 is in line with the indicator 38. This swings the load 24 to the position shown by dotted lines in Figure 1 with the suspension cable 20 pulled to an angle from the vertical. Inasmuch as the amount of retraction of the block 26 to insure registry of the indicators 37 and 38 has been predetermined, the degree of departure from the vertical by the suspension cable 20 is now known.

It is to be understood that, as the hollow block 26 is retracted in the frame 25, the weight of the load has exerted a longitudinal pull upon the link 34 and rod 32 with consequent inward movement of the cross-head 27, against the pressure of the spring 36, within the hollow block 26 and consequent movement of the indicator 39 along the face of the poundage scale 40. With the parts at rest in their thus attained positions, the indicated poundage reading is taken from the scale 40 and this, in connection with the other known factors, may be resolved into the approximate weight of the load 24 by a simple mathematical calculation.

For example, and with especial attention to Figure 5, let it be assumed that, with the parts in initial positions, the distance from the suspension point A to the laterally swinging point B (the length of the suspension cable 20 to the pivot pin 22) is sixty inches. It is desired to cause the cable to be swung ten degrees from the vertical. To determine the necessary retraction of the block 26 to effect this, the sine of 10° , which is .17364, is reckoned for sixty inches. This calculation produces 10.419 inches, which is substantially $10\frac{1}{2}$ inches. Hence, it is necessary that the retraction be such that when the indicators 37 and 38 are in registry, the distance along the chord at a right angle to the vertical from the initial line A—B to the point C (to which the pivot pin 22 is pulled) be $10\frac{1}{2}$ inches. This is predetermined, and proper adjustment is initially positioned. The indicated poundage reading is now taken on the scale 40. Let it be assumed that this reading is one thousand two hundred six pounds. Inasmuch as the angle B A C is known as 10° and the right angle between the line A B and the established chord is 90° , the angle between the line A C and the established chord must necessarily be 80° . The poundage reading of 1206 is now multiplied by the tangent of 80° , which is 5.67128, and the product, 6839.56368, is the approximate weight, in pounds, of the load 24.

It is, of course, obvious that by varying the length of the link 34, the apparatus may be adapted for use when the trolley 17 is disposed otherwise than centrally upon the bridge 14, as, for instance, against either of the stops 15a, see Figure 1.

Other variations in construction readily suggest themselves. For instance, the retraction of the hollow block 26 in the frame 25 might be ef-

fected electrically rather than manually. In this case, construction such as illustrated in Figure 4 could be adopted. In this modified structure, the screw stem is eliminated and a cable 43, fast to the outer face of the hollow block 26, passes about a drum 44 mounted on a shaft 45, which may be rotated by means of an electric motor 46 through the interposition of a worm 47 on the motor shaft 48 and intermeshing worm wheel 49 on the drum shaft 45.

Many other modifications will as quickly suggest themselves to those skilled in the art, and it is to be understood that all such are contemplated as forming a part of this invention insofar as they fall within the scope of the following claims.

What I claim is:

1. A load weighing apparatus, comprising supporting means to freely and pendulously suspend said load at rest to the action of gravity from a single fixed point at a predetermined distance from said load, means for laterally displacing in a vertical plane said pendulously suspended load through an arc of a circle of predetermined angular degree, and force measuring means cooperating with said displacing means.

2. A load weighing apparatus, comprising supporting means to freely and pendulously suspend said load at rest to the action of gravity from a single fixed point at a predetermined distance from said load, means for directly engaging the lower extremity of said supporting means to laterally displace in a vertical plane said suspended load through an arc of a circle of a predetermined angular degree, and force measuring means in-

terposed between said supporting means and load displacing means to determine the pull exerted to sustain said load in its displaced position.

3. A load weighing apparatus, comprising means for pivotally, vertically and freely suspending a load, a fixedly mounted frame, a member adjustable in respect to said frame, load engaging means slidably mounted on said member, and force indicating means cooperating therewith and disposed laterally of said load to displace the same upwardly in an arc about the pivot from which it is suspended.

4. A load weighing apparatus, comprising means for pivotally, vertically and freely suspending a load, a fixedly mounted frame, a member adjustable in respect to said frame, means for adjusting the same, load engaging means slidably mounted on said member, and force indicating means cooperating therewith and disposed laterally of said load to displace the same upwardly in an arc about the pivot from which it is suspended.

5. A load weighing apparatus, comprising means for pivotally, vertically and freely suspending a load, a fixedly mounted frame, a load measuring means adjustably mounted thereon and disposed laterally of said load, and load engaging means attached to said load measuring means to displace said load upwardly in an arc about the pivot from which it is suspended.

6. A load weighing apparatus, comprising means for pivotally, vertically and freely suspending a load, a fixedly mounted frame, a spring scale adjustably mounted thereon and disposed laterally of said load, means for adjusting the same, and load engaging means attached to said spring scale to displace said load upwardly in an arc about the pivot from which it is suspended.

7. A load weighing apparatus, comprising means for pivotally, vertically and freely suspend-
